UNITED STATES PATENT OFFICE.

AMANDA T. JONES, OF NEW YORK, N. Y.

LIQUID-FUEL FURNACE.

1,114,769.

Specification of Letters Patent. Patented Oct. 27, 1914.

Application filed July 17, 1911. Serial No. 638,902.

To all whom it may concern:

Be it known that I, AMANDA T. JONES, a citizen of the United States, residing at New York city, in the borough of Brooklyn and State of New York, have invented certain new and useful Improvements in Liquid-Fuel Furnaces, of which the following is a specification.

This invention relates in general to liquid fuel furnaces and more particularly to furnaces for burning liquid fuel and aims to improve the general construction of furnaces of this character and to provide novel and improved mechanism for feeding and distributing the oil to the combustion chamber of the furnace.

It has been found by experimentation and repeated tests that oil burning furnaces which consume large quantities of fuel oil can not be successfully and practically operated under conditions of forced draft when the fuel is fed to the combustion chamber through burners constructed to operate upon the injector principle, for the reason that complete combustion of the oil so delivered can not be effected, and the unconsumed carbon particles will escape from the combustion chamber and be delivered from the furnace in large quantities in the form of a heavy black smoke. In my present invention, I aim to overcome this heretofore objectionable feature in oil-burning furnaces by effecting complete combustion of all the carbon particles so that little, if any smoke is given off even when forced draft is demanded, and in order to accomplish this result, I have provided mechanism for feeding the oil to the combustion chamber, under the influence of gravity, in thin attenuated streams or drops which fall into the revolving flame established in my novelly constructed combustion chamber where they are completely consumed.

It is also an object of my invention to provide a specially constructed roof for my combustion chamber through which the liquid fuel percolates and which roof may be easily and readily removed for the purpose of renewal should it eventually suffer from wear and tear.

An additional object of the invention is to provide improved distributing devices which will distribute the oil evenly and uniformly to the combustion chamber and, furthermore, to provide mechanism for delivering the oil to the distributing devices and

for automatically maintaining a requisite predetermined level of oil in the distributors and, also to provide a regulating device by means of which the quantity of oil may be manually controlled and the feeding mechanism adjusted to the requirements of the furnace.

Other aims and objects and many of the advantages of my invention will be apparent as it becomes better understood by reference to the following description when considered in connection with the accompanying drawings illustrating one preferred embodiment thereof.

On the drawings—Figure 1 is a diagrammatic view partially in section of a boiler equipped with my invention. Fig. 2 is a transverse sectional view taken on the line 2—2 of Fig. 1. Fig. 3 is a horizontal sectional view on the line 3—3 of Fig. 1; and Fig. 4 is a detail plan view of the regulating device on the float chamber.

On the drawings, 5 designates the boiler which may be of any well known or preferred construction, in front of which is located the flue 6 open at the top and extending down partially in front of the combustion chamber 7. Above the combustion chamber the flue is extended laterally to form a chamber or cul-de-sac 8 in which are located the oil distributors 9. The flue is provided with sliding doors 10 and 11 for the purpose of permitting access to the boilers for cleaning the flues or repairing the boiler when occasion requires.

The bridge wall 12 which forms the rear wall of the combustion chamber is of suitable form to cause reverberation of the flame within the chamber so that the oil particles delivered thereto from above will be completely consumed before the flame is drawn through the throat 13 around the boiler and to the stack. The combustion chamber itself, is equipped with a plurality of arches 14 (best shown in Figs. 1 and 2) which are adapted to support the perforated slabs 15 preferably formed of refractory brick material or similar substance. In the drawings I have shown three arches supporting two perforated slabs but it will be obvious that the number of slabs and arches employed will vary according to the width of each individual furnace. The distributors 9, as shown in Fig. 2, preferably of V-shape in cross-section, are arranged in a series transversely of the furnace and each is provided

with a centrally disposed longitudinally extending partition 16 which divides the distributors into two compartments and insures a distribution of fuel from both sides of each distributor. The ends 17 of the distributors are higher than the sides to prevent the overflow of the oil at the ends such as might occur in marine boilers as the result of the rolling and pitching of the ship. The sides of the distributors are provided with overflow notches or nipples 18 through which the oil overflows through the slabs 15. The perforations in the slabs 15 are preferably so arranged that one perforation is disposed directly beneath each of the overflow nipples 18 and, in each perforation is positioned a tube or nipple 19 preferably made of metal and provided with an enlarged cup-shaped top 20 to receive the oil from the distributors. In the operation of the furnace the oil drips from the distributor into the cups from whence it passes through the tubes and falls in attenuated streams or drops into the furnace where it is consumed by the reverberating flame. Should the tubes or nipples 19 become coated or stopped up with an accumulation of viscous or dried oil the slabs may easily be pulled out from their places, above the furnace through the door 21 in the front of the flue whereupon the nipples may be removed individually from the slabs and cleaned or replaced by new tubes.

A leveler 22 is located transversely of the flue in front of the lateral chamber 8 and is connected with each of the distributors through a short pipe 23 through which the oil flows from the leveler to the distributors. The leveler is preferably closed, as shown in Fig. 1, and in order that the oil may rise to the required level therein, I have provided a short vent pipe 24 through which air and gas may escape. The leveler is supplied with oil through a pipe 25 from any suitable source of oil supply and a hand-valve 26 is provided at the lowest point in the pipe to enable the leveler and distributors to be drained when desired. A hand-valve 27 may also be located in the upright part of the pipe 25 so that the pipe 25 connecting with the source of oil supply may be drained without draining the leveler and distributors, if desired, by opening the valve 26 and closing the valve 27. The oil is maintained at the proper level in the leveler and in the distributors by an automatic controlling mechanism which I will now describe.

In the pipe 25 there is disposed a float chamber 28 which is adapted to contain a quantity of oil and in which is located a float 29. The contracted upper end of the chamber is threaded as indicated at 30, to receive a similarly threaded cap 31. A valve 32 is disposed in the pipe 25 above the float

chamber and from the body of this valve extends an operating arm 33 which opens and closes the valve 32 as its outer end is lowered and raised. A tube or sleeve 34 provided at its lower end with a radial flange 35 is slidably mounted in the cap 31 and the upper end of the tube is provided with an eye or loop 36 adapted to fit over the outer end of the arm 33. The float 29 is equipped with a stem 37 which projects upwardly into the tube 34 and this stem is adjustably connected with the tube by means of a set-screw 36 which passes through the opening in the tube and is threaded through a collar 38 slidably mounted on the stem 37. When the mechanism is first assembled and adjusted the valve 32 is opened and the level of the liquid is permitted to rise in the float chamber and in the leveler and the distributors until it nearly overflows through the nipples 18 of the distributors. At this instant the valve 32 is closed by the automatic rise of the lever 33 under the action of the rising float 29, which will rest upon the liquid in the float chamber. The set-screw 36 being loosened it will be evident that the float stem 37 will slide freely in the sleeve 34 until the float assumes its normal position. The set-screw 36 is thereupon tightened to rigidly connect the float stem 37 with the tube 34. Should it now be desirable to permit the oil to overflow from the distributors into the combustion chamber, the cap 31 may be screwed down upon the contracted portion of the float chamber until the oil overflows in the desired quantity. It will be evident that as the cap is screwed down the valve 32 will be correspondingly opened and by adjusting the position of the cap the quantity of oil delivered to the combustion chamber may be regulated to a fine degree of accuracy.

In order to insure against careless adjustment of the cap 31, I have provided on its upper face a series of designation marks 39 and have fixed on the float chamber an indicator 40 so that if the position of the regulating cap relatively to the indicator is noted when the furnace is operating satisfactorily, this same adjustment may be readily attained at any future time by turning the cap until it is brought into the same relative position with respect to the indicator. A glass gage 51 is also provided through which the height of the fuel in the float chamber may be noted and a hand-valve 52 is provided in the pipe 25 which may be closed should it be desirable at any time to drain the leveler and distributors without draining the float chamber.

A series of twyers 41 open at one end into the lower part of the flue 6 and at their other end into the combustion chamber. A rod or bar 42 is disposed transversely of the furnace upon which the twyers are support-

ed. It will be noted that the front of the combustion chamber is open at the bottom, as indicated at 43, to permit air to be drawn at this point directly into the furnace. The 5 twyers which open into the flue are adapted to deliver air from the flue into the combustion chamber at a point some little distance above the floor of the chamber. In order to provide for forced draft in the combustion chamber, I employ a steam pipe 44 10 connected with any suitable source of steam supply and preferably provided with a regulating valve 45. This steam pipe terminates in a transversely extending pipe 46 which is 15 provided with a plurality of branches 47, each entering one of the twyers 41, as shown in Fig. 1. The pipe 44 is provided with a turn buckle coupling 48 by means of which the length of the pipe may be regulated so 20 that the branches may be pushed farther into the combustion chamber or withdrawn to secure the best results. Once the proper adjustment of the branches 47 relatively to the twyers has been attained, it is seldom 25 necessary to further manipulate the turn buckle or to further adjust the branches or the twyers. It will be obvious that when steam is admitted to the twyers through the branches 47, an injector action will take 30 place and air together with the steam will be delivered under pressure to the combustion chamber to produce the required forced draft.

In order that the furnace may be quickly 35 and readily started and in order that an unusually hot fire may be produced in cases of emergency, I have equipped the floor of the combustion chamber with a series of oil pans 49, each being connected with a pipe 40 50, which communicates with any suitable source of oil supply. When it is desired to utilize these pans for starting the furnace or 55 in cases of emergency as has been noted, the oil is admitted to the pans from any suitable source of supply and may be ignited in the 60 combustion chamber. The flame produced from the ignition of this oil will readily ignite the oil which is then admitted through the perforated slabs from the roof 65 of the combustion chamber and once the furnace has been started and the supply of oil from the distributor is regulated, the furnace will then continue to run without the assistance of the pans 49 and the oil supply thereto may be shut off. This under 70 method of feeding may be omitted from the smaller sizes of furnaces if desired. The peculiarly constructed bridge wall 12 in conjunction with the bottom draft through 75 the opening 43 and also in conjunction with the forced draft set up by the twyers 41, will cause the flame in the combustion chamber to roll upon itself and reverberate so that the attenuated streams and drops of oil 80 fed to the chamber by the distributor will

drop into the center of the flame and be completely consumed in the chamber, leaving no unburned carbon particles to be carried through the flues, and thereby obviating the thick heavy smoke which has heretofore 70 been one of the objectionable features in oil burning furnaces, especially when required to do heavy or forced work.

I claim:

1. In an oil burning furnace, the combination of a lever, a plurality of distributor connected therewith, a combustion chamber located beneath said distributor, a pipe for supplying fuel to said lever, means for controlling the supply of fuel to the lever, 80 and means including a plurality of nipples for conveying the oil from the distributor to the combustion chamber.

2. In an oil burning furnace, the combination of a combustion chamber, a lever, 85 means for supplying liquid fuel thereto, a plurality of distributor above said combustion chamber connected with said lever and arranged to distribute the fuel throughout the area of the combustion chamber, a vent 90 connected with the top of said lever to permit the liquid to rise therein, and a valve disposed in said supply pipe whereby the lever and distributor may be drained.

3. In an oil burning furnace, the combination of a combustion chamber, a closed lever, a vent located in the top thereof, whereby to permit liquid to rise in said lever, a plurality of open-topped distributor arranged above said combustion chamber and 100 connected with said lever, a partition dividing each of said distributor into two compartments, and means for maintaining a level of liquid in said lever sufficient to 105 cause a steady but restricted overflow from said distributor.

4. In an oil burning furnace, the combination of a combustion chamber, a flue arranged in the front wall of said furnace and having a lateral chamber extending over the 110 combustion chamber, a series of open-topped distributor disposed in said lateral chamber, longitudinal partitions dividing each of said distributor into a plurality of compartments, a lever arranged in said flue 115 and connected with each of said distributor, means for maintaining a predetermined level of fuel oil in said lever and distributor, and a series of twyers communicating with said flue beneath the lever and with said 120 combustion space.

5. In an oil burning furnace, the combination of a combustion chamber, an open-topped flue, a lateral chamber extending from said flue over the combustion chamber, 125 a plurality of distributor arranged in said lateral chamber, and one or more perforated slabs disposed between said combustion chamber and said lateral chamber, the perforations in said slabs being arranged in 130

vertical alinement with the sides of said distributors to conduct the liquid fuel from said distributors to the combustion chamber.

5. 6. In an oil burning furnace, the combination of a combustion chamber, one or more perforated slabs forming the top thereof, a plurality of distributors located above said slabs, and a plurality of removable tubes or 10 nipples arranged in the perforations in said slabs through which the liquid fuel is fed from the distributors to the combustion chamber.

7. In an oil burning furnace, the combination of a combustion chamber, a perforated slab forming the top of said chamber, and a plurality of tubes or nipples having cup-shaped upper ends disposed in the perforations of said slab and adapted to distribute 20 the liquid fuel from above said slab to the combustion chamber.

8. In an oil burning furnace, the combination of a combustion chamber, a plural-

ity of arches formed therein, a slab supported on said arches and forming the top 25 of the combustion chamber, oil distributing means disposed above said slab, and removable nipples disposed in the perforations in said slab and adapted to feed the liquid fuel from said distributors to the combustion 30 chamber.

9. In an oil burning furnace, the combination of a combustion chamber, a plurality of fuel pans disposed in the floor thereof, means for supplying fuel to said pans, perforated 35 slabs forming the roof of said chamber, oil distributors located above said slabs, a normally opened draft space formed in the front of said combustion chamber, and a plurality of twyers disposed in said draft 40 space and adapted to supply air under pressure to the chamber.

AMANDA T. JONES.
